UNITED STATES PATENT OFFICE.

ROBERT E. FRAME, OF MICHIGAN CITY, INDIANA, ASSIGNOR TO FRANK X. MUDD, OF CHICAGO, ILLINOIS.

POULTRY-CAR.

1,191,294.

Specification of Letters Patent. Patented July 18, 1916.

Application filed November 18, 1914. Serial No. 872,723.

To all whom it may concern:

Be it known that I, ROBERT E. FRAME, a citizen of the United States, and resident of Michigan City, county of Laporte and 5 State of Indiana, have invented certain new and useful Improvements in Poultry-Cars, of which the following is a specification, and which are illustrated in the accompanying drawings, forming a part thereof.

10 The invention relates to improvements in cars especially adapted for the shipment of poultry and which are usually provided with a large number of coops arranged in vertical order at each side of the car, a central aisle being provided into which the 15 several coops open.

20 The invention appertains to the doors for the coops, and consists of mechanism such as is hereinafter described and which is illustrated in the accompanying drawings, in which—

25 Figure 1 is a detail longitudinal central vertical section of a car, Fig. 2 is a detail elevation of one of the walls of the aisle, Fig. 3 is a detail side elevation partly in section, of one of the aisle stanchions and a coop door applied thereto, and Fig. 4 is a detail side elevation of one of the stanchions showing the door holding keeper.

30 The body of the car 10 may be of any desired construction, and is provided with aisle stanchions 11, 12, as many in number as may be desired, preferably formed of channel bars having their flanges faced inwardly toward the center of the car. The several coops (not shown) are arranged in vertical order between adjacent stanchions, and each coop is closed at its aisle end by a door, as 13. The coop doors may be of any 35 desired form, except that each is provided with end plates 14, each having a vertical slot 15 near its lower end for the reception of a pivot pin 16. These pivot pins are set through the flanges 17, 18, of the stanchions,

40 and may be secured against longitudinal movement by means of lock nuts 21, 22. Such pins, associated with stanchions located between tiers of coops, project in both directions to support doors of each tier,

Each door is provided adjacent its upper 50 corners with latch pins 23, 24, each of such pins being preferably provided with an integral attaching plate, as 25, which may be riveted or otherwise rigidly secured to the end plate 14 of the door. A keeper plate 55 26 is rigidly secured, as by means of rivets, to a flange of the stanchion, and co-operates with the latch pin, as 23, to hold the door closed.

The keeper plates preferably loop outwardly from the stanchion intermediate of their ends, and each is provided with a laterally-opening downwardly extending recess 27 for receiving the latch pin, the slots 15 in the end plates of the door permitting the latter to be raised to allow the latch pin to enter the keeper recess and then lowered to lodge the latch pin within the downward extension of the recess.

In order to guard against accidental opening of the door due to the jarring of the car in travel, the keeper 26 is slightly out of line with the hinge pin 16 so that the door is normally tilted inward when closed. Furthermore, the downward extension 28 75 of the keeper recess is inclined downwardly and forwardly so that upward movement of the door tilts it still farther inward. As an additional precaution against opening, the keeper recess is slightly enlarged upwardly at its inner end, as shown at 29, forming a pocket into which the latch pin will enter should the jarring be sufficient to throw the door upward to that extent, thus preventing any tendency of the door 85 to swing down should there be a lateral lurch of the car at the same time.

The construction shown and described thus provides for securely holding the door in closed position without the use of movable latches while permitting it to be readily opened and swung down upon its pivots.

I claim as my invention,—

1. In a poultry car having coops, in combination, a pair of stanchions, a downwardly 95 opening coop door pivoted to and between the stanchions and having vertical movement, a lateral stud adjacent the swinging

edge of the door, and a keeper attached to the side face of one of the stanchions and provided with a laterally opening stud-receiving recess having a downward forwardly inclined extension.

5. In a poultry car having coops, in combination, a pair of stanchions, a downwardly opening coop door pivoted to and between the stanchions and having vertical movement, studs projecting laterally from the door adjacent its swinging edge, and keepers fixed to adjacent side faces of the stanchions and each provided with a laterally opening stud-receiving recess having a downward forwardly inclined extension.

6. In a poultry car having coops, in combination, a pair of stanchions, a downwardly opening coop door pivoted to the stanchions and having vertical movement, studs projecting laterally from the door adjacent its swinging edge, and keepers fixed to the stanchions and each having a laterally opening and downwardly extending recess for receiving one of the studs, the front 25 wall of the recess extension being forwardly inclined toward its lower end.

7. In a poultry car having coops, in combination, a pair of stanchions, a downwardly opening coop door pivoted to the stanchions and having vertical movement, studs projecting laterally from the door adjacent its swinging edge, and keepers fixed to the stanchions and each having a laterally opening and downwardly and upwardly extending recess for receiving one of the studs, the downward extension of the recess being inclined forwardly at its lower end.

8. In a poultry car having a plurality of tiers of coops, in combination, a series of 40 stanchions each formed of a channel bar, bars set transversely through the flanges of the stanchions and projecting therefrom at both ends; outwardly bowed laterally recessed plates attached to the side faces of 45 the stanchions, downwardly swinging coop doors located between adjacent stanchions, each door having vertical slots in its ends for receiving an end of a transverse bar as a pivot and laterally projecting studs for engaging recesses in the bowed plates, such recesses being downwardly extended.

9. In a poultry car having a plurality of tiers of coops, in combination, a series of 55 stanchions each formed of a channel bar, bars set transversely through the flanges of the stanchions and projecting therefrom at both ends, outwardly bowed laterally recessed plates attached at the side faces of the stanchions, downwardly swinging coop doors located between adjacent stanchions, each door having vertical slots in its ends for receiving an end of a transverse bar as a pivot and laterally projecting studs for engaging recesses in the bowed plates, such re-

cesses being downwardly extended, the extensions being inclined forwardly at their lower ends.

10. In a poultry car having a plurality of tiers of coops, in combination, a series of 70 stanchions each formed of a channel bar, bars set transversely through the flanges of the stanchions and projecting therefrom at both ends, outwardly bowed laterally recessed plates attached to the side faces of the stanchions, downwardly swinging coop doors located between adjacent stanchions, each door having vertical slots in its ends for receiving an end of a transverse bar as a pivot and laterally projecting studs for engaging recesses in the bowed plates, such 75 recesses being upwardly and downwardly extended.

11. In a poultry car having a plurality of tiers of coops, in combination, a series of 80 stanchions each formed of a channel bar, bars set transversely through the flanges of the stanchions and projecting therefrom at both ends, outwardly bowed laterally recessed plates attached to the side faces of the stanchions, downwardly swinging coop doors located between adjacent stanchions, each door having vertical slots in its ends for receiving an end of a transverse bar as a pivot and laterally projecting studs for engaging recesses in the bowed plates, such 85 recesses being downwardly extended and their lower ends being offset inwardly with reference to the transverse bars.

12. In a poultry car having a plurality of tiers of coops, in combination, a series of 90 stanchions each formed of a channel bar, bars set transversely through the flanges of the stanchions and projecting therefrom at both ends, outwardly bowed laterally recessed plates attached at the side faces of 95 the stanchions, downwardly swinging coop doors located between adjacent stanchions, each door having vertical slots in its ends for receiving an end of a transverse bar as a pivot and laterally projecting studs for engaging recesses in the bowed plates, such recesses being downwardly extended and their lower ends being offset inwardly with reference to the transverse bars.

13. In a poultry car having coops, in combination, a pair of stanchions, a downwardly opening coop door pivoted to the stanchions and having vertical movement, a lateral stud adjacent the swinging edge of 105 the door, a keeper attached to the side face of the stanchion and comprising a bowed strap having a laterally opening recess, such recess having a downwardly and forwardly inclined extension.

14. In a poultry car, in combination, a pair of uprights, a downwardly opening door pivoted to the uprights, its pivot pins

being capable of vertical movement, studs
projecting laterally from the door adjacent
its swinging edge, and keepers for the studs
associated with the uprights, each keeper
5 having an inverted L-shaped recess for re-
ceiving one of the studs, the wall of the re-
cess being provided with a deflecting shoul-

der for guiding the stud inwardly as it
moves upwardly in the recess.
